UNITED STATES PATENT OFFICE.

ARCHIBALD B. HORNE, OF SPRINGFIELD, MASSACHUSETTS.

GOLF CLUB.

Application filed December 14, 1927. Serial No. 239,908.

This invention relates to improvements in golf clubs and more particularly to improvements in the shafts of the club. An object of the present invention is to provide safety means for preventing the head from flying off in the event of the breaking of the shaft and possibly inflicting serious injury to nearby persons. It is a well known fact that the metal tubing comprising the golf club shaft often breaks and the head becomes separated when a drive is made carrying a portion of the shaft with it.

The invention broadly comprises a cable of suitable material which is located within the metal tubing of the shaft. One end of this cable is permanently attached to the upper end of the shaft and the other is permanently attached to the lower end of the shaft, whereby when the head and shaft become detached the cable would prevent the head from flying off and possibly injuring nearby persons. Other objects and nature of my invention will appear in the body of the specification and particularly pointed out in the claims.

Referring to the drawings:

Fig. 1 is an elevational view partially in section, showing the shaft of the club and the safety cable located therein.

Fig. 2 is a detailed sectional view of one end of the tubular shaft illustrating the manner of attaching this cable to the tubing.

Referring to the drawings in detail:

1 designates the metal tubular shaft of the club which is made of steel tubing, or the alloy known as duraluminum or other alloy aluminum, or other suitably springy material. 2 is the head portion of the club to which the tubing 1 is connected in any well known manner. The handle portion includes a winding 3 for the purpose of providing a good gripping surface, 4 designates the safety cable which is located within the tubing 1. This cable is composed of a bendable material such as steel strip, woven wire, an alloy of metal fibre, or other flexible material. This cable or safety device is attached at or near the opposite ends of the tubular shaft 1 by means of a series of openings 5 through which the ends of the cable are passed as shown in Fig. 2, by threading it through these openings first in one direction and then in the other, or opposite direction, as shown.

Located midway of the length of the cable 4 is a loop 6 for the purpose of supplying additional length thereto. This loop may if de-

sired be secured to the inside of the tubing by means of glue or other suitable means for the purpose of preventing noise or rattling when the club is in use. Should the head 2 become detached from the shaft 1, when in use, as for instance, at the point indicated by the line 6—6, the cable 4 would prevent the head from flying off and operate as a safety device. It is to be understood that I do not limit myself to any particular material of which the cable is composed, as I may if desired utilize animal or vegetable fibrous substances, woven wire, a woven tubing which is connected at its opposite ends to the upper and lower ends of the shaft.

From this description it will be seen that I have provided a safety device for golf clubs for the purpose set forth above.

What I claim is:

1. A golf club comprising a tubular shaft member, a head to which the shaft is attached, means located within the shaft and connected at its opposite ends to the shaft for preventing the flying off of the head in the event of the breaking of the shaft.

2. A golf club construction comprising a tubular shaft member, a flexible member located within the tubular shaft and having its lower end connected at or near its head portion and its upper end connected at or near the handle portion for preventing the head from flying off in the event of the breaking of the shaft.

3. A shaft for golf clubs comprising metal tubing, a wire of woven material secured at its opposite ends to the shaft.

4. A shaft for golf clubs comprising a metallic tubular member, a flexible member therein and formed with a loop intermediate of its ends and connected to the ends of the tubular member, whereby the normal flexure of the shaft will be maintained.

5. In a golf club, the combination with the head and a hollow shaft, a member located within the hollow shaft and attached at its ends to the handle and club head, and means intermediate of its length for securing the member to the interior of the hollow shaft.

6. A golf club shaft comprised of steel tubing, a steel wire in the shaft and attached at its opposite ends to the opposite ends of the tubing by means of openings in the tubing through which the steel wire is passed.

ARCHIBALD B. HORNE,
